DIFFUSION PUMPS

Tamotsu Sone, Tokyo, Japan

Application October 25, 1957, Serial No. 692,290

Claims priority, application Japan November 1, 1956

6 Claims. (Cl. 230—101)

This invention relates to improvements in diffusion pumps.

Heretofore, an oil diffusion pump, functionates in such a manner that oil vapor after ejected from a nozzle throat forms a high speed stream and the circumferential portion of the stream carries away gas molecules into a chamber beyond the nozzle. The central portion of the vapor stream proceeds forward without contributing for the aspiration of gas.

An evacuating system of a moderately high vacuum class generally consists of a high vacuum diffusion, a booster diffusion, and a backing mechanical pump. The necessity of the booster diffusion pump is caused by the ineffectiveness of the high vacuum diffusion pump for a backing pressure produced by the mechanical pump. If the high vacuum diffusion pump is sufficiently effective for higher backing pressure as mentioned, the booster pump would be ommissible.

In the conventional structure, only one tube is provided for one nozzle throat to functionate as a pump, said tube being made, in addition, to actuate as a condenser for oil vapor. It has been considered, in general, that, in order to aspirate gas contained in a single chamber through a number of aspirating tubes, it is necessary to use as many number of nozzle throats as the aspirating tubes.

Meantime, it is required that oil vaporization should be effected as much as possible in quantity out of the whole quantity of oil as small amount as possible at a temperature as low as possible in order to keep the thermal decomposition of the oil as little as possible.

One object of this invention is to provide an oil diffusion pump capable of speeding up an evacuating operation.

Another object of this invention is to provide an oil diffusion pump whereby a booster pump is not necessary in a moderately high vacuum evacuating system.

Still another object of this invention is to provide an oil diffusion pump mechanically rigid enough against a vacuum condition.

Further another object of this invention is to provide an oil diffusion pump wherein the evaporation of oil takes place quite smoothly.

A still further object of this invention is to provide an oil diffusion pump which may be set somewhat inclined.

Briefly stated in accordance with one aspect of this invention, there is provided an oil diffusion pump comprising a boiler and a cylindrical body which is divided into a high vacuum chamber and a low vacuum chamber and comprises an inner assembly and an intake line, said inner assembly being arranged concentrically with said body and comprising a nozzle through which a stream of vapour of said oil is made to flow, the peripheral portion of said stream drawing gas molecules within said high vacuum chamber, and said drawn gas molecules being carried by the central portion of said stream into said low vacuum chamber.

The invention will be better understood and other objects and additional advantages of the invention will become apparent upon perusal of the following description

2

taken in connection with the drawings, and the scope of the invention will be defined in the appended claims.

In the drawings, illustrating some of many possible embodiments of the mechanical features of this invention:

5 Figure 1 is a schematic vertical sectional view of a simple embodiment;

Figure 2 is a schematic vertical sectional view of an embodiment provided with a number of drawing-in openings;

10 Figure 3 is a schematic vertical sectional view of one of the most preferred embodiments;

Figure 4 is a schematic lateral sectional view taken on the line 4—4 of Figure 3;

Figure 5 is a sectional view on an enlarged scale showing a trap for the return of oil; and

15 Figure 6 is a schematic vertical axial sectional view of a still another embodiment.

Similar numerals refer to similar parts throughout the several views.

Referring now to Figure 1, there are a boiler 11 and a 20 cylindrical pump body 41. The boiler 11 is made of glass and provided with a neck 13. The bottom 15 of the boiler 11 is inflated slightly. An electric heating unit 17 is provided inside the bottom 15 in a position as low as possible. The electric heating unit 17 is adapted to be energized suitably.

The neck 13 of the boiler 11 is an integral part with a barrel or the wall 45 of the cylindrical body 41 of the pump, which extends vertically upwards. The body 41 is provided with an intake line 51 which inclines upwards 30 outwardly. Inside and concentrically with the body 41, there is an inner assembly comprising a guiding element 61, an invertedly frustro-conical nozzle 71, a spacing collar 93, a frustro-conical diffusing element 127, and an inverted cup 129. The inner assembly is made of metal sheets and interconnected by some fins (not shown) arranged vertically and supported by the annular bottom 49 of the body 41.

The bottom of the guiding element 61 is adapted to engage with the neck 13 of the boiler 11 leaving a peripheral 40 narrow clearance for the return of oil. Therefore, when condensed oil fills up the clearance, no oil vapor is permitted to pass through it. The nozzle 71 is attached to the top of the guiding element 61. Therefore, the oil vapor is permitted to pass through the single nozzle throat 69 only. The spacing collar 93 is arranged closely above the top 73 of the nozzle 71 which is larger than the bottom of the collar 93 in diameter so as to form an annular orifice 91 therebetween. The inner end of the intake line 51 is positioned generally below the level of the top 73 of 50 the nozzle 71. The diffusing element 127 is arranged closely above the top of the collar 93 which is smaller than the bottom of the diffusing element 127 so as to form an annular opening 125 therebetween. Around the top portion of the diffusing element 127, there is the inverted cup 129 which divides the inside of the body 41 into two

55 chambers, a high vacuum chamber 141 and a low vacuum chamber 149. The periphery of the inverter cup 129 engages with the wall 45 of the body 41 leaving some clearance therebetween so as to pass the condensed oil downwards. An exhaust line 53 is attached to the top of the lid 55 of the body 41.

In operation, an oil, for example, Silicone oil D. C. 65 702 or 703, is heated to vaporize in the boiler 11 by energizing the electrical heating unit 17. The vapor of the oil conducted into the guiding element 61 and then the throat 69 of the nozzle 71 forms a high speed stream in the nozzle 71. The peripheral portion of the oil vapor stream thus formed is projected from the annular orifice 91 towards the wall 45 of the body 41 above the level of the intake line 51, while the central portion of the oil vapor stream is conducted substantially vertically through the spacing collar 93 into the diffusing element

127. The peripheral portion of the oil vapor stream is ejected from the annular orifice 91 and forms an invertedly frusto-conical partition of the oil vapor which divides the high vacuum chamber 141 into two regions, the high vacuum region 143 and the low vacuum region 145. Thus the high vacuum region 143 is communicated with the intake line 51. Gas molecules in the high vacuum region 143 diffuse into the oil vapor partition and are carried thereby into the low vacuum region 145.

The central portion of the oil vapor stream passing through the spacing collar 93 and then the diffusing element 127 aspirates gas molecules in the low vacuum region 145 through the annular opening 125. The gas-carrying oil vapor stream is released from the top of the diffusing element 127 into the low vacuum chamber 149 where the oil vapor is condensed into a liquid state, while the gas is exhausted out of the low vacuum chamber 149 through the exhaust line 53 by means of a mechanical pump (not shown). The oil condensed at the low vacuum chamber 149 is collected on the wall 45 of the body 41 and the periphery of the inverted cup 129, returns back into the high vacuum chamber 141 through the clearance prepared along with the periphery of the inverted cup 129, flows down along the wall 45 of the body 41, and returns back into the boiler 11 through the clearance around the bottom of the guiding element 61.

Referring now to Figure 2 showing a modified embodiment, there are two frusto-conical drawing-in collars 77 and 81 and a diffusing collar 89 between the nozzle 71 and the spacing collar 93 of the foregoing embodiment. There are three annular drawing-in openings 75, 79, and 87 between the top 73 of the nozzle 71 and the lower frusto-conical drawing-in collars 77, between the frusto-conical drawing-in collars 77 and 81, and between the upper one 81 thereof and the diffusing collar 89. The annular orifice 91 is provided between the diffusing collar 89 and the spacing collar 93, the top of the diffusing collar 89 being larger than the bottom of the spacing collar 93 in diameter.

By virtue of the three drawing-in openings 75, 79, and 87, gas molecules within the high vacuum region 143 of the high vacuum chamber 141 are drawn very effectively into the peripheral portion of the oil vapor stream emitted from the diverging nozzle 71 and passing through the three collars 77, 81, and 89. The major part of the gas-carrying oil vapor stream is jetted from the annular orifice 91 into the low vacuum region 145 of the high vacuum chamber 141 while the central portion of the oil vapor stream which carries less gas molecules passes upwards vertically through the spacing collar 93. Furthermore, the oil vapor stream jetted from the annular orifice 91 aspirates gas molecules from the high vacuum region 143 into the low vacuum region 145 directly through an annular orifice provided between the wall 41 of the body 45 and the outer periphery of the diffusing collar 89. Within the low vacuum region 145 of the high vacuum chamber 141 the gas-carrying oil vapor is condensed by being cooled at the wall 45 of the body 41 separating the gas molecules which will be drawn again through the drawing-in opening 125 by the central portion of the oil vapor stream not yet diffused with gas molecules enough.

Referring now to Figures 3 and 4, one of the most preferred embodiments of this invention will be explained. In this embodiment a special boiler 11 having a three-bulged side is used. The side of the boiler 11 comprises three annular bulges 21, 23, and 25 and two annular grooves 27 and 29 between the two of the bulges, respectively, and is surrounded by a sheet 31 of a heat-conductive material along the annular bulges 21, 23, and 25, and the annular grooves 27 and 29. The boiler 11 is further wrapped by a sheet 33 of an electrical insulating material outside the heat-conductive sheet 31. Outside the insulating sheet 33, at the same time in the grooves 27 and 29, side electrical heating units 35 and 37 are arranged, respectively, which can be energized

7 together with the bottom electrical heating unit 17 by some suitable means. Preferably, the electrical heating units 17, 35 and 37 may be controlled individually.

Inside the body 41 having the wall 45, the intake line 51 and the exhaust line 53, as in the foregoing embodiments, a more complicated assembly is contained. The assembly includes an upper inverted cup 129 and a lower inverted cup 105, of which the former divides a chamber 149 positioned in the uppermost portion from a chamber 147 positioned in the intermediate portion and the latter divides the chamber 147 from a chamber 141 positioned in the lowermost portion of the body 41.

The guiding element 61 has an annularly inflated skirt 63 at the lowermost end of the element 61. The skirt 63 is provided with a number of vertical grooves 65 whereby the skirt 63 is kept in close contact with the inside of the neck 13 of the boiler 11 so that condensed oil is allowed to pass the clearance when the oil stays there to an extent. An umbrella 67 is provided around an upper portion of the nozzle 71, resting on the shoulder of the body 41 so as to support the whole assembly thereon associating with three vertical fins 155. Between the periphery of the umbrella 67 and the shoulder of the body 41, a clearance is provided so as to pass the returning oil while preventing any oil vapor originated by the re-evaporation from leaking. Similarly to the embodiment shown in Figure 2, three drawing-in collars 77, 81, and 85, a first diffusing collar 89, a spacing collar 93, and a drawing-in collar 97 are arranged between the nozzle 71 and the lower inverted cup 105. The first diffusing collar 89 is a flat trumpet-shaped one. The bottom of the spacing collar 93 is positioned somewhat deep inside the diffusing collar 89. A jet of oil vapor entrained with gas through the series of four drawing-in openings 75, 79, 83, and 87 is emitted from the annular first orifice 91 provided between the diffusing collar 89 and the spacing collar 93 and draws the gas molecules in the high vacuum region 143 by the invertedly frusto-conical partition of the entrained oil vapor up to the wall 45 of the body 41 also through an annular orifice provided between the wall 41 of the body 45 and the outer periphery of the diffusing collar 89. And thus the partition divides the high vacuum chamber 141 into the high vacuum region 143 and the low vacuum region 145, as in the foregoing embodiments.

The lower inverted cup 105 is supported by a second diffusing collar 103 which rests on the drawing-in collar 97, an annular drawing-in opening 99 being provided therebetween. Gas released from the entrained oil vapor partition within the low vacuum region 145 is drawn through the annular openings 95 and 99 by the rather fresh oil vapor stream positioned at the near center of the nozzle 71 and passing nearer the centers of the collars. Then the peripheral portion under consideration of the oil vapor stream thus entrained is emitted through a second annular orifice 117 provided between the second diffusing collar 103 and another spacing collar 119 into the intermediate chamber 147. An auxiliary collar 115 is extended upwards from the inner periphery of the inverted cup 105. An outer concentric annular orifice 151 is thus provided between the bottom of the auxiliary collar 115 and the top of the second diffusing collar 103 through which gas molecules are aspirated from the region 145 into the intermediate chamber 147 by the oil vapor stream jetted from the annular orifice 117.

The entrained oil vapor released into the intermediate chamber 147 is condensed by the cold wall 45 of the body 41 and returned to the high vacuum chamber 141 along the wall 45 through a trap provided along the periphery of the lower inverted cup 105. A clearance is kept between the wall 45 of the body 41 and the periphery of the lower inverted cup 105 and an annular flange 107 is extended downwards from the periphery. A trap ring 109 having an inflated skirt 111 is suspended from the periphery of the lower inverted cup 105. Thus a trap for gas is

formed as shown in Figure 5. The inflated skirt 111 is arranged in close contact with the wall 45 by means of a number of vertical grooves 113.

Gas released from the oil vapor within the intermediate chamber 147 is drawn again by a still more central portion of the oil vapor stream passing through the spacing collar 119 and drawing-in collars 123 and 127. For the drawing-in of gas the annular drawing-in openings 121 and 125 are provided between these collars, respectively.

Around the top of the uppermost drawing-in collar 127 an upper inverted cup 129 is arranged and constructed with another trap ring 131 similarly to the lower inverted cup 105. Thus the upper inverted cup 129 is provided with a flange 137 and the trap ring 131 is provided with an inflated skirt 133 having a number of vertical grooves 135. Another outer concentric annular orifice 153 corresponding to the outer concentric annular orifice 151 is provided between the inner periphery of the upper inverted cup 129 and the top of the uppermost drawing-in collar 127 whereby gas within the intermediate chamber 147 is drawn into the low vacuum chamber 149.

It will be seen that the most peripheral portion of the oil vapor stream passing upwards through the nozzle 71 acts at first to draw in gas molecules and is then condensed releasing the gas which is drawn by the intermediately peripheral portion of the oil vapor stream and then released by the condensation of the second-named portion of the oil vapor stream, and at last the released gas is drawn in by the most central portion of the oil vapor stream and carried thereby into the low vacuum chamber 149.

The uppermost member of the inside assembly is a transparent funnel 139 made of, for example, glass and rested on the top of the upper inverted cup 129 concentrically. This is an only part made of glass within the construction of the inner assembly. The glass funnel 139 functionates a gauge indicating the degree of vacuum. That is, in the early period of the evacuating operation, a condensed oil ring may be found inside the glass wall of the funnel 139. The ring ascends gradually along the wall as the vacuum improves and at last disappears from the top of the wall of the glass funnel 139. Subsequently, another ring of the condensed oil may be found inside the glass wall 45 of the low vacuum chamber 149 which ring also ascends as the process of the evacuating operation. At last such a ring may not be found anywhere. In the light of experiences, those skilled in the art may estimate the degree of vacuum by the position of the ring.

The oil condensed in the low vacuum chamber 149 is collected along the clearance provided between the wall 45 of the body 41 and the periphery of the upper inverted cup 129 and returned on the wall 45 of the intermediate chamber 147 through the trap provided along said clearance. The condensed oil flowing down along the wall 45 of the intermediate chamber 147 is similarly collected along the clearance provided between the wall 45 and the periphery of the lower inverted cup 105 together with the oil condensed within the intermediate chamber 147 and returned on the wall 45 of the high vacuum chamber 141. The condensed oil flowing further along the wall 45 is collected along the clearance provided around the skirt 63 of the guiding element 61 and returned into the boiler 11. The returned oil flows along the specially shaped side wall of the boiler 11 into the lot of the oil accumulated on the bottom 15. Now by virtue of the special shape of the side wall of the boiler 11 and action of the side electrical heating units 35 and 37 explained hereinbefore, the down-flowing oil is heated so as to be re-vaporized extremely smoothly resulting in that there is no fear of oil bumping. On the other hand, the upper part of the wall 45 of the body 41 may be cooled externally, for example, by means of arranging a coil of water pipe around the part through which cold water may be passed.

By virtue of the arrangement of collars with openings provided therebetween, the oil condensed inside the collars from the flowing oil vapor which passes through the collars is expelled through the openings out of the collars so as to keep the inside from obstruction caused by the condensed oil against the passage of the oil vapor stream.

While up-jet oil diffusion pumps only have been disclosed hereinbefore as embodiments of this invention, it should be understood that this invention is not limited to such particular arrangements disclosed and the principle of this invention may be applied for other arrangements of diffusion pumps. To this end still another embodiment is illustrated in Figure 6 schematically wherein a pump is arranged laterally. Parts thereof are similar to those described with respect to the embodiment shown in Figure 1. It is considered that it is not necessary to explain the arrangements and functions of this pump particularly.

By virtue of this invention, a vacuum of 10^{-6} mm. Hg could be achieved in a certain case within a period of 20 seconds while it is necessary to take a period of a matter of 70 minutes in order to achieve the same degree of vacuum by means of a most effective pumping system of a conventional type. Furthermore, an auxiliary mechanical pump of less capacity will suffice by this invention than the conventional type of the diffusion pump.

Many modifications within the scope of the invention described above will be apparent to those skilled in the art without a departure from the inventive concept. I do not wish to be limited to the forms herein particularly shown and specifically described, but rather intend that the invention shall include all reasonable equivalents thereof.

I claim:

1. An oil diffusion pump comprising a boiler, a cylindrical body disposed above and communicating with said boiler, said body being divided into a high vacuum chamber and a low vacuum chamber and having an inner assembly, an exhaust line communicating with said low vacuum chamber, and a descending intake line, said inner assembly being arranged concentrically with said body and comprising a tapered nozzle through which a stream of oil vapor is made to flow, a heating element located in heating relation to said boiler adjacent the narrow end of said tapered nozzle, said intake line entering said cylindrical body adjacent said tapered nozzle, a frusto-conical spacing collar having its wide end adjacent the wide end of said nozzle, the wide end of said spacing collar being of less diameter than the wide end of said nozzle and spaced therefrom, a frusto-conical diffusing element having its wide end adjacent but spaced from the small end of said spacing collar, said last mentioned wide end being of greater diameter than said small end of said spacing collar, said tapered nozzle, said frusto-conical spacing collar and said frusto-conical diffusing element being disposed in said high vacuum chamber, said frusto-conical diffusing element having its narrow end terminating in said low vacuum chamber, the peripheral portion of said stream drawing gas molecules within said high vacuum chamber, and said drawn gas molecules being carried by the central portion of said stream into said low vacuum chamber.

2. An oil diffusion pump comprising a boiler, a cylindrical body arranged vertically on and communicating with said boiler, said body being divided into a high vacuum chamber and a low vacuum chamber positioned above the former, and having a vertically arranged inner assembly and a descending intake line, an exhaust line communicating with said low vacuum chamber, said inner assembly being arranged concentrically with said body and comprising a tapered nozzle through which a stream of oil vapor is made to flow, a heating element located in heating relation to said boiler and disposed adjacent the narrow end of said tapered nozzle, said intake line

entering said cylindrical body adjacent said tapered nozzle, a frustro-conical spacing collar having its wide end adjacent the wide end of said nozzle, the wide end of said spacing collar being of less diameter than the wide end of said nozzle and spaced therefrom, and a frustro-conical diffusing element having its wide end adjacent but spaced from the small end of said spacing collar, said wide end of said frustro-conical diffusing element being of greater diameter than said small end of said spacing collar, said tapered nozzle, said frustro-conical spacing collar and said frustro-conical diffusing element being disposed in said high vacuum chamber, and said frustro-conical diffusing element having its narrow end terminating in said low vacuum chamber, the peripheral portion of said stream drawing gas molecules within said high vacuum chamber, and said drawn gas molecules being carried by the central portion of said stream into said low vacuum chamber.

3. An oil diffusion pump comprising a boiler, a cylindrical body divided into a high vacuum chamber and a low vacuum chamber, said boiler having a neck and a heating element associated therewith to evaporate oil therein, said body being arranged vertically on and communicating with said boiler and including an inner assembly, a descending intake line, and an exhaust line communicating with said low vacuum chamber, said inner assembly being arranged concentrically within said body in said high vacuum chamber and comprising a guiding element, a nozzle, a spacing collar, a diffusing element, and an inverted cup, said guiding element being adapted to contact with said neck of said boiler and leaving a peripheral clearance for returning oil, said nozzle being supported on said guiding element so as to introduce the whole quantity of oil vapor only through said nozzle, said spacing collar being arranged above the top of said nozzle and the bottom of said spacing collar being smaller in diameter than said top of said nozzle, said diffusing element being arranged above said spacing collar and the bottom of said diffusing element being larger than the top of said spacing collar, said inverted cup being arranged around the top portion of said diffusing element and across the inside of said body and leaving a peripheral clearance for returning oil, said intake line being in communication with a high vacuum region of said high vacuum chamber, said region being defined by the wall of said body, said guiding element, said nozzle and an oil partition film formed by the peripheral portion of the oil vapor stream jettied from an annular orifice formed between the top of said nozzle and the bottom of said spacing collar, gas within said high vacuum region and said intake line being carried by the jettied partition into a low vacuum region separated from said high vacuum region by said oil partition film within said high vacuum chamber, the gas carried by said partition into said low vacuum region being drawn through an annular opening provided between the top of said spacing collar and the bottom of said diffusing element by the central portion of said oil vapor stream passing through the spacing collar and the diffusing element into a low vacuum chamber arranged above said inverted cup, the oil being condensed out of the gas-carrying vapor within said low vacuum chamber and returned to the boiler through said clearances, and the gas released from the oil being admitted into said exhaust line.

4. In an oil diffusion pump as claimed in claim 3, a transparent funnel extended from the inverted cup into the low vacuum chamber, through which the whole quantity of oil vapor stream is introduced into said low vacuum chamber.

5. An oil diffusion pump comprising a boiler, a cylindrical body divided into a high vacuum chamber and a low vacuum chamber, said boiler having a neck and a heating element associated therewith to evaporate oil therein, said body being arranged on and communicating

with said boiler and comprising a generally cylindrical wall, an inner assembly, a descending intake line and an exhaust line communicating with said low vacuum chamber, said inner assembly having members arranged 5 concentrically with said body and comprising a guiding element, an inverted frustro-conical nozzle, a first frustro-conical drawing-in element, a first diffusing element, a first spacing collar, a second frustro-conical drawing-in element, a second diffusing element, a second spacing collar, a third frustro-conical drawing-in element, and a transparent funnel arranged vertically in the order stated, the bottom of each of said drawing-in elements and diffusing elements being larger in diameter than the top of a member positioned directly below so as to 10 provide an annular opening therebetween, the top of each of said diffusing elements being larger than the bottom of a member positioned directly above in diameter so as to provide an annular orifice therebetween, said guiding element being adapted to engage with said neck 15 of the boiler and leaving a peripheral clearance for returning oil, said nozzle being supported on said guiding element so as to introduce the whole quantity of the oil vapor stream only through said nozzle, inverted cups being supported around the tops of said second diffusing 20 element and said third drawing-in element and adapted to divide the inside space of said body into a high vacuum chamber, an intermediate vacuum chamber, and a low vacuum chamber, clearances for returning the oil being left between the peripheries of said inverted cups and said wall, and the top of said first diffusing element being positioned higher than the level of the junction of said 25 intake line and said wall, an oil partition film formed by the oil vapor stream emitted from the annular orifice provided between said first diffusing element and said first spacing collar, dividing said high vacuum chamber into a high vacuum region communicating with said intake line and a low vacuum region, whereby gas molecules within said high vacuum region are drawn in through 30 openings provided under said first drawing-in element and said first diffusing element by the peripheral portion of the oil vapor stream emitted from said nozzle and drawn in by the oil vapor film, the major portion of the 35 gas molecules thus drawn in being released into said low vacuum region and again drawn in through openings provided under said second drawing-in elements and said second diffusing element by the peripheral portion in 40 question of the oil vapor stream passing therethrough, and a major portion of the gas molecules thus drawn in being released into said intermediate vacuum chamber, 45 again being drawn in through openings provided under said third drawing-in element by the peripheral portion of the oil vapor stream passing therethrough and released through said transparent funnel into said low vacuum 50 chamber whence the gas molecules are exhausted out of the pump through an exhaust line and the oil vapor cooled condenses into a liquid state and is returned to 55 said boiler along said wall.

6. In an oil diffusion pump as claimed in 5, said boiler having an annular multiple-bulged side, an annular groove being provided between any proximate two of said bulges, a sheet of insulating material and a sheet of heat conductive material, said side being surrounded by said sheet of a heat-conductive material which is further surrounded by said sheet of electric insulating material, and an electrical heating unit being arranged in each of said grooves outside of said insulating material, said heating element being arranged in said boiler, said heating units and said heating element being selectively energizable singly and in combination.
